UNITED STATES PATENT OFFICE

2,317,457

METHOD OF MAKING SCREEN CLOTH

Richard D. Heller, Columbus, Ohio

Original application May 23, 1941, Serial No. 394,846. Divided and this application October 15, 1941, Serial No. 415,046

3 Claims. (CL 140—7)

This invention relates to screen cloth, and one of the objects of the invention is an improved method of making a unique screen cloth which is particularly adapted for use in vibratory apparatus which operates to convey unscreened material along such screen cloth without undue wear or injury.

A further object of the invention is an improved method of attaching a cross-strip to a parallel wire screen cloth intermediate the ends thereof, so as to have a maximum surface engagement with the wires of such screen cloth to reduce to a minimum the tendency of such cross-strip to become detached from such wires during operation of the screen cloth.

More particularly it is the object of the present invention to provide an improved method of attaching to a parallel wire screen cloth a plurality of contiguous metal cross-wires and soldering a cross-strip to all of the wires to produce a cross-strip composed of such cross-wires and said cross-strip soldered to each other and soldered to the parallel wires of the screen and thereby reduce to a minimum the tendency of the cross-strip to become detached during operation of the screen cloth.

Other objects of the invention will appear hereinafter, the novel features and combinations being set forth in the appended claims.

In the accompanying drawing:

Fig. 1 is a plan view of a completed screen cloth embodying my improvements;

Fig. 2 is an enlarged edge view of one of the intermediate cross-strips shown in plan in Fig. 1;

Fig. 3 is a side view of the screen cloth of Fig. 1;

Fig. 4 is an end view of a vibratory deck with my improved screen cloth mounted thereon;

Fig. 5 is an enlarged perspective view showing a portion of one of the intermediate cross-strips shown in plan in Fig. 1;

Fig. 6 is another enlarged perspective view similar to Fig. 5 but taken from a different angle; and

Fig. 7 is a sectional elevation of preferred mechanism for carrying out my improved method of soldering a flat cross-strip to one side of the wires of the screen cloth and a plurality of contiguous wires to the other side of the screen cloth to complete a cross-strip having a maximum engagement with surfaces of the wires of the screen cloth.

This application is a division of my co-pending application S. N. 394,846, filed May 23, 1941, for an improvement in Screen cloth; for the purpose

of illustrating the mounting of the screen cloth shown in Fig. 1 I have shown in Fig. 4 the preferred screen cloth mounting mechanism illustrated in the drawings of my co-pending application S. N. 273,328, filed May 12, 1939, for an improvement in Screens.

The method herein disclosed relates particularly to the construction of spaced-apart cross-strips 79, 79 intermediate the end bars 56, 56, 10 of a screen cloth comprising a plurality of substantially straight or non-woven wires preferably made of high carbon Swedish steel known as bright music or piano wires. As pointed out in my Patent No. 2,220,106 granted Nov. 5, 1940, 15 for an improvement in Screen cloth and method of making same, this type of screen cloth wire is very hard and tough and consequently has a very long life in an operating screen cloth, thus making it extremely desirable for this purpose. 20 That patent relates to improvement in the end bars of a screen of this type whereas the herein disclosed invention relates to the spaced-apart cross-strips 79, 79 intermediate the end bars, as indicated in the above-mentioned objects of the 25 present invention. While my improvements herein disclosed are particularly adapted for use in vibratory screening apparatus they may have a general application in various types of screening mechanisms.

30 As shown in Fig. 4, the vibratory deck frame 10 is provided with attaching anchorages 43 and 55 for receiving the end bars 73 and 56 respectively of the screen cloth shown in plan view in Fig. 1. The attaching anchorage 43 is 35 fixed to the deck frame whereas the anchorage 55 is connected to screen tension mechanism 50. The cross-strips 79, 79 serve as bearing areas between the screen cloth and the elongated strips of wood 38, 38, which rest in elongated troughs 39, 39 mounted on supports secured rigidly to the cross beams one of which is shown at 23 in Fig. 4.

35 The method of attaching the cross-strips 79, 79 to the parallel wires 31, 31 of the screen cloth will now be described. A support 77 coextensive with the width of the screen panel 51 of Fig. 1, or coextensive with the length of the cross-strips 79, is provided with a plurality of spaced-apart lifting screws 155 which are threaded through 40 the elongated channel member 145 which is also of the same length as that of the cross-strip 79. 45

Along the channel member 145 extends a heater element 151 having a bottom plate 150 serving as a bearing strip for engagement by the 50 upper ends of the spaced lifting screws 155.

Mounted on the heater element 151 is an elongated metal tray 153 having its bottom lined with a strip of asbestos 153'. An elongated hot plate or bar 81 rests in the tray 153 in the asbestos strip 153'.

The hot plate or bar 81 is provided with a center elongated groove 82 coextensive with the cross-strip 79. In this groove 82 is placed a plurality of strands of wire 83 which may be of the same constituency as wires 31. The groove 82 is treated to preclude solder adhering thereto.

Upon supporting the screen cloth by anchoring the end bars thereof in fixed and stationary positions, and lifting the plate 77 to in turn lift the channel 145, the side strips 147, 147 may be forced against the bottoms of the wires 31, 31 and held there with the plate 77 in fixed and stationary position. This may be done by means of the apparatus disclosed in the parent application S. N. 394,846.

With the parts adjusted as illustrated in Fig. 7, the wires 83 will be forced into intimate contact with the wires 31 and the strip of solder which is laid above the wires 31 on the wires 83, is melted, after a reasonable heating period, by the heat from the heater element 151.

As disclosed in my parent application, Serial No. 394,846, tensioning mechanism may be applied to one end of the screen cloth while the other end is connected to a fixed anchorage so that the parallel wires of the screen cloth may be held taut during the operation of soldering the cross-strips thereto. While the solder is in molten condition an elongated rectangular strip 84 of tin plate (sheet iron coated with tin) is laid on top of the wires 31 whereupon the electric current to the heater 151 is cut off and the solder allowed to solidify with the tin plate strip 84 soldered to one side of the wires 31 and the transverse wires 83 soldered to the other side of the wires 31, thereby producing the cross strip connection 79.

The illustration in Fig. 2 is reversed from that of Fig. 7 because Fig. 2 shows the operating position of the screen cloth with the wires 83 on top thereof while Fig. 7 shows the wires 83 in the elongated trough 82 in the top of the hot plate 81.

I prefer to locate the wires 83 on the upper side of the screen for two reasons. In the first place, the wires 83 are much stronger and much more durable than the tin plate strip 84, being steel piano wires of the same constituency as the screen wires 31, and therefore have a long life notwithstanding the fact that they are subject to great stresses and strains during movement thereover of the unscreened materials. In the second place, for a given width and length of cross strip the lower area of contact of the wires 83 with the solder is about 57% greater than the area of contact between the solder and the metal strip 84 and consequently the resistance against detachment offered by the wire cross-strip on top is much greater than would be offered by the plate 84 if it were placed on top.

In my copending application, S. N. 390,386, filed Apr. 25, 1941, now Patent No. 2,283,881, granted May 19, 1942, for an improvement in Apparatus for making screen cloth, as a division of my parent application S. N. 346,342, filed July 19, 1940, now Patent No. 2,283,878, granted May 19, 1942, I have described and claimed the apparatus for anchoring the ends

of the screen cloth and subjecting the screen cloth to tension to hold the parallel wires taut, combined with apparatus for adjusting the elevation of the support 77 shown in Fig. 7.

5 In my co-pending application S. N. 273,328, filed May 12, 1939, for an improvement in Screens, I have disclosed and claimed the mechanism shown in Fig. 4 for mounting the screen on the deck of vibratory apparatus in crown formation.

Obviously those skilled in the art may make various changes in the details and arrangement of parts without departing from the spirit and scope of the invention as defined by the claims 15 hereto appended, and I therefore wish not to be restricted to the precise construction herein disclosed.

Having thus described and shown an embodiment of my invention, what I desire to secure by 20 Letters Patent of the United States is:

1. The method of soldering a cross-strip of a plurality of wires to the wires of an unwoven parallel wire screen panel which comprises the positioning of the cross-strip of wires at one 25 side only of the screen panel by fitting the cross-strip of wires in a shallow flat bottomed rectangular trough in a hot plate with each of the last-named wires in contact with the next adjacent wire, and soldering the said cross-strip of wires to the screen panel by applying sufficient heat to the said hot plate, while the flat bottom of the said trough holds the wires of the cross-strip in contact with the wires of the screen panel and while the spaced-apart sides of the 30 said trough hold the cross-strip with each wire thereof in contact with the next adjacent wire.

2. The method of soldering cross-strips to the wires of an unwoven parallel screen panel which 35 comprises the positioning of a plurality of cross-wires at one side of a screen panel by placing the cross-wires in an elongated trough of a hot plate in parallelism with each other and bringing such wires in the trough in contiguous relation with only one side of the screen panel, 40 said trough having a depth approximately equal to the diameter of each of said cross-wires and a width approximately equal to the combined diameters of said cross-wires so that the wires in the trough occupy a plane parallel to a plane 45 extending through said panel wires, and soldering the cross-wires to each other and to the wire strands of the screen panel by applying heat to 50 said hot plate.

3. The method of making screen cloth which 55 comprises attaching connecting end bars to a plurality of parallel strands of wire to form an unwoven plane screen panel, subjecting the panel to tension by exerting a pulling force on one connecting bar while the other is anchored, holding 60 a plurality of contiguous cross-strip wires in rectilinear rectangular formation in a plane parallel with the plane of the screen panel with each wire in contact with the next adjacent wire and with all of the cross-strip wires in contact 65 with the wire strands of the screen panel on only one side of the latter intermediate the connecting bars thereof, and while the cross-strip wires are thus held soldering them to said screen panel wires on said one side and to each other to rigidly 70 connect the cross-strip wires to the screen panel wire strands.

RICHARD D. HELLER.
